[57] **CLAIM**

The ornamental design for a pennant for a bicycle, as shown and described.

DESCRIPTION

FIG. 1 is a perspective view of a pennant for a bicycle showing my new design, it being understood that the broken lines are for illustrative purposes only; FIG. 2 is a front elevational view thereof, the rear being substantially a mirror image of the front shown; FIG. 3 is a left side elevational view thereof; FIG. 4 is a right side elevational view thereof; FIG. 5 is a top plan view thereof; and FIG. 6 is a bottom plan view thereof.
